C. W. THOMPSON

VEHICLE SPRING

Filed Mar. 24, 1922

UNITED STATES PATENT OFFICE.

CLARANCE W. THOMPSON, OF WILMINGTON, DELAWARE, ASSIGNOR TO THOMPSON SPRING COMPANY, OF WILMINGTON, DELAWARE, A CORPORATION OF DELAWARE.

VEHICLE SPRING.

Application filed March 24, 1922. Serial No. 546,401.

To all whom it may concern:

Be it known that I, CLARANCE W. THOMPSON, a citizen of the United States, residing at Wilmington, in the county of New Castle 5 and State of Delaware, have invented certain new and useful Improvements in Vehicle Springs, of which the following is a specification.

This invention relates to spring devices 10 formed and arranged to be associated with an axle or other load-sustaining member of a running-gear and with a member of the body or equivalent load-carrying part, so that relative movements resulting from 15 shocks, thrusts, and stresses arising from irregularities in the roadway over which the vehicle travels may be absorbed.

The invention relates particularly to such 20 a device arranged to be associated with a leaf-spring acting as a support for the body or equivalent load-carrying part, one or both ends of such a spring being connected swingably with a spring-restrained member of the device in order that it readily may flatten 25 or elongate and return to a more arcuate condition under the influence of road and load action.

One of the objects of the invention is to 30 provide a buffer of novel and efficient form arranged to restrain both the flattening tendency of the leaf-spring and its tendency to bodily movement under the influences to which it is subjected during operation of the vehicle with which it is associated.

35 When considered in connection with the description herein, the characteristics of the invention will be apparent from the accompanying drawings, forming part hereof, wherein an embodiment of the invention is disclosed, for purposes of illustration.

Although the disclosures herein exemplify what now is considered to be a preferable embodiment of the invention, it is to be understood that it is not the intention to be 45 limited necessarily thereto in interpretation of the claims, as modifications and adaptations within the limits of the claims can be made without departing from the nature of the invention.

50 Like reference-characters refer to corresponding parts in the views of the drawings, of which—

Fig. 1 is a vertical section;

Fig. 2 is an elevation; and

55 Fig. 3 is a view of a buffer member.

Having more particular reference to the drawings, 4 designates an axle part, such for example as a brake-drum, which constitutes a member of the running-gear of a vehicle, to which is secured by a fastening 60 5 an upstanding bracket member 6.

The member 6 carries, and preferably is formed integrally with, a casing 7, which preferably is cylindrical. The casing has at or near its lower end a closure member 8 65 constituting an end wall and abutment that extends laterally from the bracket. The casing is closed at its upper end by a removable cap 9.

A hollow piston or stress-sustaining member 10 is slidable longitudinally in, and has a fairly close fit with, the side wall of the casing, by which it is guided, and it has a head or partition 11 at or near its upper end.

70 A rod 12 extends centrally through, and is connected adjustably with, the partition-head, and it extends downwardly therefrom through the end wall 8 to the outside of the casing. The rod is connected with the head in any suitable manner. For example, its 75 upper portion, as shown, may be screw-threaded and have thereon opposed nuts 13, one on each side of the head. On removing the cap 9 and thus having access to the interior of the casing, the upper nut may be 80 turned off the rod, the piston withdrawn, and the lower nut turned to the place that will permit the piston to assume the desired position on the rod. The piston then is 85 replaced with its head against the lower nut 90 and the upper nut turned down against it. In this way the extension of the rod outside 95 of the casing and the relative tension of opposing springs hereinafter mentioned may be adjusted.

95 The rod 12 extends through a member 14, which is mounted inside of the casing by having a threaded lower bushing portion 15 turned into a threaded opening in the lower end wall 8. The member 14 is formed with 100 an annular abutment 16 on which seats the lower end of an inner coil-spring 17. An outer coil-spring 18 is disposed between the end wall 8 and the piston-head 11. The 105 springs 17 and 18 are arranged to resist movement of the piston in response to outward movement of the rod. The inner spring 17 is shorter than the outer spring 18, so that its resistance to movement of the piston does not occur until after initial 110

compression of spring 18. The spring 18 is of such strength that it will resist ordinary movement of the piston, but, when the piston under comparatively violent stresses is moved sufficiently to come into action against spring 17, further resistance to its movement, of course, then occurs.

A rebound spring 19 is interposed between the piston-head and the cap 9, and it cushions and absorbs the inward or rebound movement of the rod 12.

The member 14 contains a packing-space 20, which is closed by a threaded gland 21 screwed into the bushing 15. The gland is formed with an exterior flange 22.

The lower end of the rod 12 is connected by swingable links or plates 23 with the end of an arcuate leaf spring 24, which latter is a supporting member of the body or equivalent portion of the vehicle.

During the relative stress action between the rod and a leaf-spring so connected with it while the vehicle is in operation, the latter spring lengthens and shortens as it flattens from and returns to arcuate disposition, and body movement in a direction longitudinal of the spring also occurs at times. This results in swinging movement of the links or plates 23. In order to restrain such swinging movement toward the bracket member 6, a buffer device is associated with the bracket. The buffer device also is arranged to resist abnormal outward movement of the rod 12.

One element of the buffer device is a strong member 25 of spring sheet material and of generally arcuate form. In its upper portion it is curved to conform substantially to the bend where the end wall 8 of the casing extends laterally from the bracket, and it is secured to the bracket and held with its upper curved portion in that bend by suitable fastenings, such as screws 26. The member 25 also may be further secured by having its upper end portion interposed between the end wall 8 and the flange 22 of the packing-gland.

The member 25 in its lower portion curves and extends outwardly from the bracket toward the link-connected end of the leaf-spring, and it is related and proportioned

with respect thereto in such manner that the lower portion of the link connection between the spring and the rod 12 will contact with the member on extraordinary swinging movement toward the bracket. The buffer member thus operates to restrain, absorb, and gradually stop movement of the end of the spring toward the bracket, whether it occurs as a result of flattening of the leaf-spring or of body movement.

Moreover, the buffer member 25 is so positioned that it will be contacted by, and restrain the relative movement of the parts when the rod is moved to an unusual extent outwardly of the casing under extraordinary stresses.

In order to increase the resistance of the buffer member 25, a spring 27, preferably of coil form, is interposed between the lower portion of that member and the bracket.

Having thus described my invention, what I claim as new, and desire to secure by Letters Patent, is—

1. In a vehicle, the combination of an upstanding bracket, an abutment extending laterally therefrom, a spring on said abutment, a rod arranged to compress said spring extending below said abutment, a body-supporting member, a member connecting said member and rod, and a sheet-material spring-buffer secured to said bracket below said abutment and curving outwardly from said bracket and arranged to restrain movement of said connecting member. 75

2. In a vehicle, the combination of an upstanding bracket, an abutment extending laterally therefrom, a spring on said abutment, a rod arranged to compress said spring extending below said abutment, a body-supporting member, a member connecting said member and rod, a sheet-material spring-buffer member secured to said bracket below said abutment and curving outwardly from said bracket and arranged to restrain movement of said connecting member, and a spring interposed between said buffer member and said bracket. 90

In witness whereof, I affix my signature. 95

CLARANCE W. THOMPSON. 100
